SUCTION CATHETER FLOW REGULATOR OR SIMILAR ARTICLE

Ravindra K. Badkar, Playa Del Rey, Calif., assignor to
Pharmaseal Laboratories, Glendale, Calif., a corpora-
tion of California

Filed Jan. 24, 1966, Ser. No. 729

Term of patent 14 years

(Cl. D16—1)

FIG. 1.

FIG. 2.

FIG. 3.

FIG. 4.

FIG. 5.

FIG. 6.

FIGURE 1 is a side elevational view of the suction catheter flow regulator or similar article;

FIGURE 2 is a top plan view thereof;

FIGURE 3 is a bottom plan view thereof;

FIGURE 4 is a left end elevational view thereof;

FIGURE 5 is a right end elevational view thereof;

FIGURE 6 is a sectional view taken along line 6—6 of FIGURE 1; and

FIGURE 7 is a sectional view taken along line 7—7 of FIGURE 1.

The dotted line showing of the peripheral tubing retainers adjacent each end of the suction catheter flow regulator or similar article is for illustrative purposes only.

I claim:

The ornamental design for a suction catheter flow regulator or similar article, as shown and described.
